UNITED STATES PATENT OFFICE.

ENOCH H. ABRAHAM, OF UNIONTOWN, PENNSYLVANIA, ASSIGNOR TO COVINGTON DOOR JAMB COMPANY, A CORPORATION OF MAINE.

DOOR-JAMB FOR COKE-OVENS.

No. 873,479.

Specification of Letters Patent.

Patented Dec. 10, 1907.

Application filed November 30, 1906. Serial No. 345,590.

To all whom it may concern:

Be it known that I, ENOCH H. ABRAHAM, a citizen of the United States, and resident of Uniontown, Fayette county, State of Pennsylvania, have invented new and useful Improvements in Door-Jambs for Coke-Ovens, of which the following is a specification.

My invention relates to an improvement in door jambs for use in connection with what is known as the "beehive" type of coke oven, and particularly for use in connection with that class of beehive coke oven from which the coke is drawn by mechanical means.

In the ordinary method of drawing beehive coke ovens by mechanical devices, a shovel is introduced, which is mounted at the end of a reciprocating bar on some sort of machine which moves the shovel into the coke furnace underneath the coke, moves it from side to side as may be deemed necessary, and subsequently draws the same and by mechanical means or otherwise discharges the coke therefrom.

In the practice as it now exists in construction the door is formed of fire clay jambs and arch blocks. Now in the mechanical drawing of the coke, the inserting and drawing of the apparatus that withdraws the coke or discharges the coke, comes in contact with the bottom jamb on either side of the door, and these jambs as now constructed of fire clay are very susceptible of damage by the contact of the implement used in this method of extracting. As a result the lower jamb rapidly becomes worn away, and being the foundation of the entire door, results in the destruction of the entire arch. Heretofore various efforts have been made to obviate this difficulty but without success. Now I have discovered that where a cast iron bottom jamb is used and is extended far enough into the coke oven to protect the door frame from the effect of the contact with the coke extractor but not sufficiently far to come in contact with the extreme heat of the oven, a much more permanent structure is secured.

The invention will be best understood by a reference to the accompanying sheets of drawings, in which

Figure 1 is a plan view of an ordinary beehive oven on the line 1—1 of Fig. 2; Fig. 2 is a vertical section of the oven on the line 2—2

of Fig. 1, showing the construction; Fig. 3 is 55 a front view of the door; Fig. 4 is a plan view of the jamb; Fig. 5 is a side view of the jamb, and Fig. 6 is an end view of the jamb.

In the drawings A represents the oven, C the bottom of the furnace, and D the door; 60 O the opening in the top, and K the top wall; 1, 2 and 3 represent the jamb blocks, 3 being the jamb shown in Figs. 4 and 5, put in place. The jamb consists of a casting of iron or other suitable metal, substantially 65 of the form shown in Fig. 4. The outer end f is substantially at right angles to the inner face of the jamb, and is provided with an end e which turns in and serves to cover the 70 jamb in the wall. The inner end terminates in an appropriate curve d as shown, and is provided at any convenient point with one or more webs c which serve to strengthen and stiffen the casting. The spaces between the webs c and end f of the jamb, are 75 filled in with brick and fire clay B in the ordinary manner, but the space between the end d and the web c is not filled in so as to permit of expansion of the metal. The jamb may be of any convenient height, but in 80 practice it will vary from 6½ to 8 inches in height. The curvature will vary from time to time according to the size of the coke oven. In practice, one of these jambs is used on either side of the door, their distance varying 85 in accordance with the width of the door. They are laid on the foundation of the oven, and the furnace is then built up over them and the bottom tiles are laid in against the 90 metal jamb.

In setting the jamb in the oven, it is so placed that the forward end will extend outward beyond the face of the ordinary red brick which is filled in on the outside of the door when the latter is closed in the ordinary 95 way. As a result the outer end of the jamb is constantly exposed to the air, which has the effect of reducing the temperature and keeping it cooler than it would be if it were covered with brick. As a result of the free 100 circulation of the air at either end of the jamb, an ordinary cast iron door jamb of the character shown will last substantially as long as the oven in which it is placed.

I claim as my invention:

1. A metal door jamb for use in connection with beehive coke ovens, conforming in curvature to the curvature of the furnace,

- and provided with a part at the inner end which is arranged not to be closed in by fire brick so as to permit of expansion and contraction.
- 5 2. The combination in the wall of a beehive coke oven, of a metal door jamb conforming in curvature to the curvature of the oven so placed that the same will not extend into the furnace to such a point as to be subjected to the extreme heat of the oven, and yet will protect the edges of the walls from destruction from coke extracting, and uninclosed by fire brick at the inner end so as to permit of expansion and contraction.
- 10 3. The combination in the wall of a beehive coke oven of a metal door jamb conforming in curvature to the curvature of the furnace, so placed at the inner end that the same will not extend into the furnace to such a point as to be subjected to the extreme heat of the oven, and extending exteriorly beyond the wall of the oven at the other end
- and uninclosed by fire brick at the inner end, so as to permit of expansion and contraction.
4. The combination in the wall of a beehive coke oven of the ordinary type, of a metal door jamb conforming in curvature to the curvature of the furnace placed at the bottom of the door on either side below the brickwork of the arch, extending a suitable distance into the interior of the oven, for the purposes of rendering the door practically indestructible to machine operation, and uninclosed by fire brick at the inner end, so as to permit of expansion and contraction. 25 30 35

In testimony, that I claim the foregoing as my invention, I have signed my name in presence of two witnesses, this 26th day of November 1906.

ENOCH H. ABRAHAM.
